UNITED STATES PATENT OFFICE.

JOHN HAYS HAMMOND, JR., OF GLOUCESTER, MASSACHUSETTS.

ANTENNA FOR RADIOTRANSMISSION SYSTEMS.

1,420,255.

Specification of Letters Patent. Patented June 20, 1922.

Application filed February 27, 1913, Serial No. 750,981. Renewed October 23, 1918. Serial No. 259,455.

To all whom it may concern:

Be it known that I, JOHN HAYS HAMMOND, Jr., a citizen of the United States, residing at Gloucester, in the State of Massachusetts, have invented certain new and useful Improvements in Antennæ for Radiotransmission Systems, of which the following is a specification.

This invention relates to antennæ, or aerial conductors, for the reception and transmission of radiant energy, and relates more particularly to antennæ on vessels, where it is impossible to get a satisfactory length of antennæ by the usual arrangement on torpedoes and other vessels of small size, and where even on large vessels the length and capacity of the antennæ can be greatly and advantageously increased by my invention.

20 In the accompanying drawings:—

Figure 1 shows my antenna attached to a torpedo or submarine boat.

Figure 2 shows my antenna attached to the stern of a boat or other vessel.

25 Figure 3 is a side elevation of my antenna as attached to a battleship.

Figure 4 is a plan of my antenna as attached to a battleship.

In Figure 1, T is a torpedo or submarine boat, M is a hollow mast on said torpedo, A is an antenna, B is a towing line, D is a towing anchor, F is a line for attaching the antenna A to the torpedo or boat, I is an insulator between antenna A and line F, G is a line for attaching the antenna A to the float C and the towing line B, G' is a line between the float C and the towing anchor D, I' is an insulator between the antenna A and the line G, L is a leading-in wire from the antenna A to the receiving and transmitting apparatus K, and W is a winch for paying out or hauling in the antenna A and the towing line B.

In Figure 2, S is a boat or other vessel, 45 N is a mast on said vessel, A' is an antenna, F' is a line for attaching the antenna A' to the vessel, I² is an insulator between antenna A' and line F'. B' is a line between float C' and the vessel S, which would act as a towing line when the vessel was under way. G² is a line for attaching the antenna A' to the float or buoy C' and the line B', I³ is an insulator between the antenna A' and the line G², D' is an anchor resting on the bottom, G³ is a line from the float or buoy C' to the anchor D', L' is a leading-in wire from the

antenna A' to the transmitting and receiving apparatus K', and W' is a winch for paying out or hauling in the antenna A' and the line B'. This arrangement shown in Figure 60 2 would be used when the vessel is at anchor, or otherwise stationary.

In Figures 3 and 4, O is a battleship; P and P' are its masts; A² is an antenna composed of four wires, a, a', a² and a³; R, R' 65 and R² are spreaders for separating the antenna wires; I⁴ are insulators between the antenna wires and spreader R; I⁵ are insulators on spreader R'; I⁶ are insulators between the antenna wires and spreader R²; B² 70 is a towing line; W² is a winch; G⁴ and G⁵ are lines connecting the spreader R² and the towing line B² with the float C²; G⁶ is a line connecting the float C² with the towing anchor D²; and L² is a leading-in wire from 75 the antenna A² to the receiving and transmitting apparatus K². While a battleship has been used for illustration here, it is evident that my antenna can be used on any other kind of vessel.

80 The floats C and C' and C² are for the purpose of keeping the antennæ out of the water, and for keeping the towing line near the surface of the water. The towing lines B, B' and B² keep the antennæ steady and prevent the latter from varying their distance from the surface of the water too much. The towing anchors D, D' and D² are preferably in the form of a propeller running on a swivel, which arrangement 85 helps to keep the propeller near the surface of the water and the towing line and antenna nearly horizontal, when the vessel is under way.

90 By this system of disposing my antenna, I can secure a far greater length and capacity of antenna than by methods heretofore in use on vessels, and the length of my antenna is not limited by the size of the vessel. The advantages derived from increasing the length and the capacity of an antenna are well known in the art of radio transmission. For instance, the antennæ on the biggest battleships at present are capable of emitting only about seven kilowatts 95 of power, and the maximum wave length that can be employed with these antennæ is only about one thousand five hundred meters; but with my extended antenna far more power can be emitted and much greater 100 wave lengths can be employed.

105 Any suitable means may be employed for

connecting the antenna with the receiving and transmitting apparatus, and any suitable arrangement may be used for winding up and letting out the antenna and the towing line, for keeping the outboard end of the towing line afloat and for other details of the construction; and in general I do not confine myself to the particular construction here shown, but changes and modifications within the knowledge of those skilled in the art, may be made in the construction shown and described herein, without departing from the spirit of my invention, provided the means set forth in the following 15 claims be employed.

Having thus described my invention, I claim:—

1. An antenna for vessels for the emission and reception of radiant energy, one end of 20 which antenna is attached to a vessel and the other end of which is attached to a towing anchor in such a manner that it shall be extended out from said vessel.

2. The combination with a vessel, of an 25 antenna for the emission and reception of radiant energy secured to said vessel and adapted to be extended outwardly therefrom, a float secured to said antenna at a point spaced from the point of connection 30 between said antenna and said vessel, an anchor, means connecting said anchor to said float, and a tow line connecting said float to said vessel.

3. The combination with a vessel, of an 35 antenna for the emission and reception of radiant energy secured to said vessel and adapted to be extended outwardly therefrom, and a towing anchor secured to said antenna at a point spaced from the point of connection 40 between said antenna and said vessel.

4. The combination with a vessel, of an 45 antenna for the emission and reception of radiant energy secured to said vessel and extending outwardly therefrom, a marine 50 float spaced from said vessel and connected to said antenna to hold said antenna in an extended position, towing means connecting said float to said vessel, and an anchor connected to said float.

5. The combination with a vessel, of an 55 antenna for the emission and reception of radiant energy secured to said vessel and extending outwardly therefrom, a float spaced from said vessel and connected to said antenna to hold said antenna in an extended position, towing means connecting said float to said vessel, an anchor spaced from said float, and means connecting said anchor to said float.

6. The combination with a vessel, of an 60 antenna for the emission and reception of radiant energy secured to said vessel and extending outwardly therefrom, a float spaced from said vessel and connected to said antenna to hold said antenna in an ex-

tended position, towing means connecting said float to said vessel, an anchor spaced from said float, means connecting said anchor to said float, and means operative to simultaneously vary the effective lengths of 70 said antenna and said towing means.

7. The combination of a vessel adapted to 75 float in a fluid medium, an antenna for the emission and reception of radiant energy secured to said vessel and arranged to be extended operably therefrom by the action of said medium thereon, and a towing anchor secured to said antenna at a point spaced apart from the point of connection between said antenna and said vessel.

8. The combination of a vessel adapted to 80 float in a fluid medium, an antenna for the emission and reception of radiant energy secured to said vessel and arranged to be drawn outwardly therefrom by the action of 85 said medium thereon, and a towing anchor secured to said antenna at a point spaced apart from the point of connection between said antenna and said vessel.

9. The combination of a vessel adapted to 90 float in a fluid medium, an antenna for the emission and reception of radiant energy secured to said vessel and arranged to be drawn outwardly upon movement of the vessel through the medium, and a towing 95 anchor secured to said antenna at a point spaced apart from the point of connection between said antenna and said vessel.

10. The combination of a movable body 100 supported by a natural medium, a towing anchor, and means interconnecting the body and the towing anchor arranged for radiant energy signalling, and automatically positioned upon movement of said body through the medium.

11. The combination of a marine body, a 105 trailer, means interconnecting said body and trailer for radiant energy signalling, and towing means for said trailer.

12. The combination with a movable body 110 movable through a surrounding medium and adapted to be controlled by radiant energy, of an extensible metallic means arranged for the reception of electromagnetic waves and arranged to be extended by movement of 115 said body through the medium.

13. In a system for the control of a body 120 movable through a natural medium by radiant energy, an extensible metallic means arranged for the reception of electromagnetic waves and arranged to be extended by movement of said body through the medium along the axis of travel of said body. This specification signed and witnessed

this 19th day of February, A. D., 1913.
